BALL PROJECTOR

Ray E. Barnes, Seattle, Wash.

Application January 19, 1948, Serial No. 3,079

1 Claim. (Cl. 124—1)

1

This invention relates to game apparatus, and more particularly to a mechanical device for kicking a ball, and resembling a human figure.

It is an object of the present invention to provide a manually operable game device for dropping and kicking a football.

It is another object of the invention to provide such a device in the form of a human figure wherein the arms and one leg are simultaneously operable for respectively dropping and kicking a football.

It is a further object of the invention to provide a device of the character described, comprising simplicity of organization, economy of construction and efficiency in operation.

The foregoing objects and others ancillary thereto are preferably accomplished by a device which is formed to resemble the human figure, and includes a body with one leg rigidly attached thereto for supporting the figure in a vertical position, the other leg being pivotally suspended from the body. A pair of arms are movably mounted on the body and extend in front of the body to terminate in hands which in closed position will grip a ball immediately above the pendulous leg. The head is provided with inclined neck portions and mounted on a plunger that is slidable vertically through the body and terminates above the pendulous leg portion rearwardly of the leg pivot. By this arrangement, when the head is depressed the arms are moved apart to release the ball from between the hands, and the pendulous leg is simultaneously cammed forward by the plunger to kick the ball after it is dropped from the hands.

The novel features that are considered characteristic of the invention are set forth with particularity in the appended claim. The invention itself, however, both as to its organization and its method of operation, together with additional objects and advantages thereof, will best be understood from the following description of a specific embodiment when read in connection with the accompanying drawing, wherein like reference characters indicate like parts throughout the several figures and in which:

Fig. 1 is a front view in elevation of a mechanical kicking device in accordance with the present invention;

Fig. 2 is a side view in elevation of the device;

Fig. 3 is a top plan view of the device;

Fig. 4 is a side view in elevation of the device in operation; and

Fig. 5 is a top plan view of the device in operation.

2

Referring now to the drawings:

The mechanical kicking device of the present invention comprises a base 14 rigidly supporting a leg 15 that in turn rigidly supports a body portion 22. A second leg 19 is pendulously supported by a pin 23 carried by the body 22 and leg 15. The pin 23 is adjacent to the forward portion of the leg 19 and the rearward top portion of the leg is curved to form a cam surface 28.

A pair of arms 20 and 21 are formed integrally with shoulders which rest on top of the body 22 and are pivotally attached thereto by pins 27 adjacent their rear inner corners. A compression spring 26 is anchored between the front portions of the arms or shoulders to pull the arms to closed position. It will be noted that the arm 20 is angularly arranged to be slightly shorter than the arm 21 so that in their closed position the ball will be held immediately above the swingable leg 19. A bore 30 extends vertically through the body 22 and opens from the bottom of the body immediately above the cam surface 28 of the leg 19. The head 16 having inwardly inclined cam-forming neck portions 17 is supported by a plunger 18 that is slidable in the bore 30. The shoulder portions of the arms 20 and 21 are recessed to accommodate the plunger 18 and cooperate with the cam surfaces 17. The plunger is slotted to receive a pin 25 to limit the movement thereof and is biased upwardly by a return spring 24.

In operation, a ball B is placed between the hands of the arms 20 and 21. To effect the kicking action, the head 16 is then manually depressed so that the neck cam surfaces 17 will bias the arms 20 and 21 apart to release the ball, and simultaneously the plunger 18 will bear down on the cam surface 28 to cause the leg 19 to swing forwardly and kick the ball B as it drops toward the leg 19.

Although a certain specific embodiment of the invention has been described, it is obvious that many modifications thereof are possible. The invention, therefore, is not to be restricted except in so far as is necessitated by the prior art and by the spirit of the appended claim.

Having described my invention I claim:

In a game apparatus, a mechanical device for kicking a ball and resembling a human figure, comprising a body portion rigidly supported by a leg fixed to a base, a central bore vertically through said body portion and opening adjacent said leg, a leg pivotally dependent from said body portion and having a cam-shaped portion rearwardly of its pivot and underlying said opening, arms pivoted to said body portion, spring means

biasing said arms toward each other to a ball-holding position, a head carried by a plunger that is slidably mounted in said bore for movement through said opening to engage said leg cam for biasing said leg forward and upward through a kicking stroke, cam-shaped neck portions on both sides of said head for biasing said arms against said spring means to release the ball as the leg is moved through the kicking stroke, and spring means biasing said head and plunger upwardly to 10 inoperative position.
